SELF-CONTAINED PORTABLE ELECTRONIC SIGNAL GENERATOR

Theodore W. Fischer, Dayton, Ohio, assignor to Dayton
Electronic Products Company, Inc., Dayton, Ohio, a
corporation of Ohio

Filed Sept. 22, 1966, Ser. No. 3,955

Term of patent 14 years

(Cl. D26—1)

FIG-1

FIG-2

FIG-3

FIG-4

FIG. 1 is a perspective view of a self-contained portable electronic signal generator showing my new design;

FIG. 2 is a side elevational view thereof;

FIG. 3 is a front elevation thereof; and

FIG. 4 is a rear elevation thereof.

I claim:

The ornamental design for a self-contained portable electronic signal generator, substantially as shown and described.
